Norwalk, Calif., assignors to Bates Industries, Inc.

Filed Oct. 12, 1973, Ser. No. 405,745

Term of patent 14 years

Int. Cl. D26—06

U.S. Cl. D48—32 R

FIG. 1

FIG. 2

FIG. 3

FIG. 4

FIG. 5

FIG. 6

FIG. 1 is a perspective view of a vehicle light showing our new design;

FIG. 2 is a front elevational view thereof;

FIG. 3 is a left side elevational view thereof, the right side elevational view thereof being a mirror image;

FIG. 4 is a rear elevational view thereof;

FIG. 5 is a top plan view thereof; and

FIG. 6 is a bottom plan view thereof.

The faceting on the front interior surface of the lens is not shown in FIGS. 5 and 6 because the faceting would not normally be visible through the lens at such an angle.

We claim:

The ornamental design for a vehicle light, substantially as shown and described.
